PLAYER-PIANO.

1,075,853.

Specification of Letters Patent.

Patented Oct. 14, 1913.

Application filed July 28, 1911. Serial No. 641,165.

To all whom it may concern:

Be it known that I, ERIC R. PHILBLADE, of Fall River, county of Bristol, and State of Massachusetts, have invented an Improvement in Player-Pianos, of which the following description, in connection with the accompanying drawings, is a specification, like letters on the drawings representing like parts.

10 This invention relates to a self playing piano or like instrument, in which pneumatic actions are employed and controlled by a perforated sheet or roll of paper passing over a tracker board.

15 In instruments of the character described, and as now commonly constructed and known to me, the tracker board is provided with ninety six holes, each connected with a pneumatic action, there being eighty eight

20 for the keys and eight auxiliary pneumatics for operating various auxiliary mechanisms, such as the mechanism for increasing and diminishing the musical tone, for regulating the feed, for rewinding the roll, for cutting

25 out the player action while the roll is being rewound, and in some instances for starting and stopping the player action automatically by means of a coin. Each of the auxiliary mechanisms in instruments as now

30 constructed and known to me requires a pneumatic action to put it into operation and a separate pneumatic action to release it or put it out of operation.

The present invention has for its object 35 to simplify, improve and cheapen the cost of instruments of the class described, and to this end, provision is made, whereby the auxiliary pneumatic which puts the auxiliary mechanism into operation also is employed to put it out of action, whereby the separate release pneumatics now commonly employed are dispensed with, and the starting auxiliary pneumatics are employed as the release pneumatics. To this end, the 40 pneumatic which actuates or controls the piano action or part thereof, is controlled by a valve, which in turn is controlled by a pneumatic governed by the paper or music sheet passing over the main tracker board, 45 and which may be designated the combined starting and stopping or release pneumatic, provision being made whereby one operation of the pneumatic will open the valve to effect the action desired, and the next opera-

tion of said pneumatic will close the valve, 55 to stop or release the said action. These and other features of this invention will be pointed out in the claims at the end of this specification.

Figure 1 is a plan view of an apparatus 60 embodying this invention. Fig. 2, a front elevation with parts in section of the apparatus shown in Fig. 1. Fig. 3, a detail of one of the valves shown in Figs. 1 and 2. Fig. 4, a section on the line 4—4 Fig. 2. 65 Fig. 5, a like section with the parts in a different position. Fig. 6, a section and elevation of a power pneumatic and the mechanism governed by it, which is controlled by the valve shown in Fig. 4. Fig. 70 7, an elevation of Fig. 6 looking toward the left, and Figs. 8 to 12 inclusive views of power pneumatics controlled by the valves of the apparatus shown in Fig. 1.

In the present instance, I have illustrated 75 the invention as embodied in three combined starting and stopping pneumatics, which control the action of four auxiliary pneumatics, one for obtaining a substantially loud effect, a second for obtaining a 80 substantially soft effect, a third for rewinding the music sheet or roll, and a fourth for cutting out or rendering inoperative the player actions while the roll is being rewound, but inasmuch as the operation of all 85 the combined starting and stopping pneumatics is the same, a detailed description of one will suffice to enable the invention to be clearly and fully understood.

Referring to Fig. 4, *a* represents a tracker 90 board of known construction and such as now used in a player piano, and *b* the perforated sheet of music which is moved over the openings *c* in the tracker board. One of the openings *c* is connected by a tube *d* with 95 the primary pneumatic of a combined starting and stopping pneumatic embodying this invention. The primary pneumatic referred to comprises a diaphragm 10 covering a chamber 12, having an air inlet passage 13 100 with which the tube *d* is connected. The diaphragm 10 supports the stem 14 of two valves 15, 16 located in a chamber 17 provided with a port 18 leading to the atmosphere through a passage 19 in the box 105 or casing 20 of the combined starting and stopping pneumatic, and with which the valve 15 cooperates. The valve chamber 17

is also provided with a port 21 with which the valve 16 coöperates, and which connects the chamber 17 with the suction or exhaust chamber 22 in the casing 20, the latter chamber having an outlet port 23, which is connected by the pipe 24, see Fig. 2, with the main bellows not shown. The valve chamber 17 is connected by a passage 25 in the casing 20 with the power pneumatic or bellows 26 suitably affixed to the lower side or bottom of the casing 20 as herein shown.

The operation of the apparatus as thus far described is the same as that of the well known pneumatics now commonly employed in player pianos, and may be briefly described as follows: When the music sheet *b* covers the opening *c* in the tracker board the valves 15, 16 are in the position shown in Fig. 4, in which position the power pneumatic 26 is connected with the atmosphere through the passage 25, valve chamber 17, port 18, and passage 19, and the chamber 17 is cut off from the suction chamber 22 by the valve 16, and the chamber 12 of the primary pneumatic and the passage 13 leading to it are connected with the suction chamber 22 through a bleeder opening 27. When the port *c* in the tracker board *a* is uncovered by a perforation in the music roll or sheet *b*, air passes through the tube *d* and passage 13 into the chamber 12 of the primary pneumatic, and acting on the diaphragm 10 lifts the valve stem 14 so as to close the valve 15 and open the valve 16, thereby cutting off the power pneumatic 26 from the atmosphere and connecting it with the suction chamber 22 through the port 21 as represented in Fig. 5.

The power pneumatic 26 in its movement from the position shown in Fig. 4 to that shown in Fig. 5 actuates mechanism for operating a valve 30, which coöperates with a port or opening 31 in the upper surface of the casing 20, said port being connected as will be described to the primary of another pneumatic action.

In the present instance the valve 30 is shown as a plate or disk, see Figs. 3 and 4, having on its under side a layer of felt 32 or like material, and provided with a curved arm 33 having holes 34, through which are extended pins 35 on the upper surface of the casing 20, said pins constituting a pivot for the valve, the holes 34 being sufficiently large to permit the valve to be raised from its closed or lowered position shown in Fig. 4 into its elevated position shown in Fig. 5. The valve 30 is raised into its open position as herein shown, by means of pins or projections 36 on the face of a ratchet wheel 37, mounted to turn on a shaft 38 supported by an upright 39 on the casing 20. The ratchet wheel 37 is turned step by step by a pawl 40, pivoted at its lower end to the inovable member of the power pneumatic 26, and

normally held by a spring 41 against a front stop 42, in position to be engaged with one of the teeth of the ratchet wheel.

The ratchet wheel 37 is provided with twice as many teeth as pins, and the latter are arranged opposite every other tooth, so that, when the power pneumatic is actuated once by uncovering the port *c* in the main tracker board *a*, the pawl 40 will turn the ratchet wheel 37 the distance of one tooth and bring a pin 36 into engagement with the arm 33, so as to open the valve 30 and uncover the port 31 to the atmosphere. When the port *c* is again covered by the music sheet *b*, the power pneumatic 26 is returned to its normal position shown in Fig. 4 by a spring 43 or otherwise and the pawl 40 is lowered into its starting position, ready to be engaged with the next succeeding tooth of the ratchet wheel, which latter remains in the position into which it has been moved and maintains the valve 30 open, until the port *c* in the main tracker board *a* is again uncovered. When this occurs, the power pneumatic 26 is again actuated and moved into what may be termed its closed position shown in Fig. 5. In this second movement of the power pneumatic, the pawl 40 is engaged with the next succeeding tooth of the ratchet wheel, and turns the latter the distance of one tooth, thereby removing the pin 36 from engagement with the arm 33 of the valve 30, and allowing the latter to drop into its normal position and close the port 31.

It will be observed, that the power pneumatic 26 effects the opening of the valve 30 and that the same pneumatic effects the closing of the said valve.

The valve 30 controls the operation of a pneumatic, which for sake of distinction may be designated an auxiliary power pneumatic, inasmuch as it is auxiliary to the pneumatics employed in the regular player action and is only occasionally used. The auxiliary power pneumatic may be of any suitable or known construction and comprises a power pneumatic, and a primary, and its power pneumatic is operatively connected to any desired portion of the mechanism according to what is to be accomplished, and inasmuch as the operation is the same or substantially the same, so far as the pneumatic is concerned, a detailed description of one with relation to the mechanism operated by it will suffice to enable the invention to be understood.

In Fig. 6 I have represented mechanism for obtaining a soft effect on the tone, which is effected by reducing the throw or range of movement of the hammers. To this end, the usual hammer 45 is moved from its full line position into its dotted line position, by moving the hammer rail or bar 46 from its full line position into its dotted line position. For this purpose, the hammer rail 46

is connected by suitable mechanism with the power pneumatic 47; said mechanism in the present instance comprising a crank 48 attached to the hammer rail, and a link 49 connected with the power pneumatic 47, provision being made for lost motion between the link 49 and crank 48 by a slot 50 in said link. The power pneumatic 47 is normally connected with the atmosphere through a passage 51 in a casing 52 leading to a valve chamber 53, having a port 54 leading to the atmosphere, and a second port 55 leading to a suction chamber 56, having the outlet port 57 connected by the tube or pipe 58 with the main bellows (not shown).

The valve chamber 53 contains a valve 60, which coöperates with the port 54, and a second valve 61, which coöperates with the port 55, and has its stem 62 extended into the suction chamber 56 and resting upon a diaphragm 63 forming a movable wall between the suction chamber 56 and a primary pneumatic chamber 64, which is connected by the tube or pipe 65 with the passage 66, in the casing 20, from which leads the port 31 controlled by the valve 30. The power pneumatic 47 is normally filled with air and is moved into its expanded position shown in Fig. 6 by a spring 67, or otherwise in a manner well understood. By reference to Figs. 4 and 6, it will be seen that the port 31 is normally closed by the valve 30 and that the primary pneumatic chamber 64 is connected with the suction chamber 56 through the bleeder opening 69. Under these conditions, the valve 61 is closed and the valve 60 is open, thereby connecting the power pneumatic 47 with the atmosphere, which enables the spring 67 to expand the power pneumatic and through the link 49 and crank 48 move the hammer rail 46 back into its full line position, thereby affording a full or maximum range of movement for the hammers 45. When however the valve 30 is open as represented in Fig. 5, air passes through the port 31 passage 66 and tube 65 into the chamber 64 of the primary pneumatic, thereby actuating the diaphragm 63 to close the valve 60 and cut off the power pneumatic 47 from the atmosphere, and at the same time the valve 61 is opened, and the power pneumatic 47 is connected with the suction chamber 56 through the passage 51 and port 55, with the result that the power pneumatic 47 is collapsed, and the hammer rail 46 is moved into its dotted line position to shorten the range of movement of the hammers and obtain a soft or softened tone, when the strings 70 of the piano are struck by the hammers 45. It will be observed that the power pneumatic 47 shown in Fig. 6 remains collapsed as long as the valve 30 shown in Figs. 4 and 5 remains open, and that the length of time the valve 36 remains open is governed by the music

sheet *b*. When the valve 30 is closed as above described, the air in the tube 65 and primary pneumatic 64 is exhausted through the bleeder opening 69, and the valve 61 is closed and the valve 60 opened, thereby connecting the power pneumatic 47 with the atmosphere and allowing the spring 67 to expand the same and restore the hammer rail to its normal or full line position.

From the above description, it will be seen that the casing 20 provided with the ports 31 constitutes in effect a supplemental or auxiliary ported board, whose ports are controlled by valves, one or more according to the number of auxiliary power pneumatics used in the instrument.

In Fig. 1 I have represented the auxiliary ported board or casing 20 as provided with three ports 31 and with three valves 30 coöperating with them. The right hand port 31 and valve 30 controlling the power pneumatic 47 connected with the hammer rail as shown in Fig. 6, and the left hand port 31 and its valve 30 controlling the power pneumatic 72 shown in Fig. 8, which is connected by mechanism comprising a link 73 and crank 74 with a damper rail or bar 75 provided with a cushion 76, which is normally engaged with the strings 70 and is designed to be removed therefrom when it is desired to obtain a substantially loud effect, which is effected by the collapsing of the power pneumatic 72; and the center port 31 and its valve 30 control the operation of two power pneumatics 80, 81 shown in Figs. 9, 10, 11 and 12.

The primary chamber 82 of the power pneumatic 80 shown in Figs. 9 and 10 is connected by the tube 83 and passage 84 with the center port 31 of the auxiliary ported board; and the primary chamber 85 of the power pneumatic 81 shown in Figs. 11 and 12 is connected with said center port 31 by the tube 86 and passage 84. The power pneumatics 72, 80 and 81 are operated and controlled in the same manner as above described with relation to the power pneumatic 47, and it is deemed unnecessary to repeat the operation in detail. The power pneumatic 80 controls the operation of a double valve 88 coöperating with ports 89, and thereby cuts in and out the player action while the music sheet *b* is being rewound. The power pneumatic 81 controls the operation of the mechanism employed to rewind the music sheet or roll, which mechanism may be such as is now commonly employed and is not herein shown. Instead of performing the particular functions herein described, the power pneumatics controlled by the auxiliary ported board and its coöperating valves may perform any other or desired functions.

From the above description it will be seen that by means of the auxiliary ported

board and its coöperating valve or valves, the power pneumatic which effects the operation of the valve to start in action any particular auxiliary mechanism, also operates the same valve to put the particular auxiliary mechanism out of action, which is the gist of the present invention, and as I believe myself to be the first to accomplish this result in a player instrument in which the power pneumatics are operated by suction, I do not desire to limit the invention to the particular construction of mechanism herein shown for accomplishing this result. The ratchet wheel 37 may be held in the position into which it is moved by the pawl 40, by a spring 90 mounted on the shaft 38 and frictionally engaging the ratchet wheel.

Claims:

1. In an apparatus of the character described, in combination a main tracker board, a power pneumatic connected therewith, an auxiliary power pneumatic, mechanism operatively controlled by said auxiliary power pneumatic, an auxiliary ported board connected with said auxiliary pneumatic, a valve coöperating with said auxiliary ported board to control the operation of said auxiliary pneumatic, a ratchet wheel provided with projections arranged to open said valve when the ratchet wheel is turned one step and to release said valve when the ratchet wheel is turned another step, and a pawl connected with the first mentioned

power pneumatic and coöperating with said ratchet wheel to turn the same when moved in one direction by the first mentioned power pneumatic, substantially as described.

2. In an apparatus of the character described, in combination, a main tracker board, a power pneumatic connected therewith, an auxiliary power-pneumatic, mechanism operatively controlled by said auxiliary power pneumatic, an auxiliary ported board connected with said auxiliary pneumatic, a valve coöperating with said auxiliary ported board to control the operation of said auxiliary pneumatic, a rotatable device provided with means for engaging said valve to open the same by movement of said rotatable device in one direction, and to pass out of engagement with and release said valve and permit it to be closed by further movement of the rotatable device in the same direction, and means operated by the first mentioned power-pneumatic for actuating said rotatable device to move it step by step in the same direction, substantially as described.

In testimony whereof, I have signed my name to this specification in the presence of two subscribing witnesses.

ERIC R. PHILBLADE.
